[57] **CLAIM**

I claim the ornamental design for a hook for a sausage conveyor, as shown.

DESCRIPTION

FIG. 1 is a perspective view of a hook for a sausage conveyor showing my new design;
FIG. 2 is a rear elevational view thereof;
FIG. 3 is a bottom plan view thereof;
FIG. 4 is a top plan view thereof;
FIG. 5 is a front elevational view thereof;
FIG. 6 is a side elevational view as seen from the right-hand side of FIG. 2; and,
FIG. 7 is a side elevational view thereof as seen from the left-hand side of FIG. 2.
